(57) **CLAIM**

The ornamental design for a housing for a vehicle instrument panel, as shown and described.

DESCRIPTION

FIG. 1 is a front perspective view of a housing for a vehicle instrument panel, as viewed from a front left side of the housing.

FIG. 2 is another front perspective view of a housing for a vehicle instrument panel, as viewed directly from the front. FIG. 3 is a rear perspective view of a housing for a vehicle instrument panel, as viewed from a rear left side of the housing.

FIG. 4 is another rear perspective view of a housing for a vehicle instrument panel, as viewed directly from the rear. FIG. 5 is a left side view of a housing for a vehicle instrument panel.

FIG. 6 is a right side view of a housing for a vehicle instrument panel.

FIG. 7 is a top side view of a housing for a vehicle instrument panel; and,

FIG. 8 is a bottom side view of a housing for a vehicle instrument panel.

The ornamental design which is claimed is shown in the drawings, with any accompanying shading of one or more surfaces. Applicant(s) reserve the right to disclaim one or more features, in whole or in part, of the claimed design as originally filed, such as any shading of one or more surfaces.

1 Claim, 8 Drawing Sheets
